UNITED STATES PATENT OFFICE.

BERNHARD EYBEL, OF NEW YORK, N. Y.

PENCIL-HOLDER.

SPECIFICATION forming part of Letters Patent No. 291,998, dated January 15, 1884.

Application filed October 4, 1883. (No model.)

To all whom it may concern:

Be it known that I, BERNHARD EYBEL, of the city, county, and State of New York, have invented certain new and useful Improvements 5 in Pencil-Holders, of which the following is a full, clear, and exact description.

Reference is to be had to the accompanying drawings, forming part of this specification, in which similar letters of reference indicate 10 corresponding parts in all the figures.

Figure 1 is a side elevation of my improvement. Fig. 2 is a sectional side elevation of the same. Fig. 3 is a sectional plan view of the same, taken through the line $x-x$, Fig. 2. 15 Fig. 4 is a sectional plan view of the same, taken through the line $y-y$, Fig. 2. Fig. 5 is a sectional side elevation of the feed-die. Fig. 6 is a side elevation of the pencil-tube. Fig. 7 is a side elevation of a pencil-lead.

20 The object of this invention is to facilitate the adjustment of the leads in pencil-holders, and promote simplicity in the construction of such holders.

The invention consists in a pencil-holder 25 constructed with a case having its lower end slitted and its lower end edge bent inward to receive and hold a die having exterior groove and interior screw-thread to move the lead out and in, the lead being held from being 30 turned by the die by an interior pencil-tube having an angular bore, as will be hereinafter fully described.

The case A of the holder may be of any convenient length and thickness, and may be 35 made of any suitable material. The upper end of the case A may be closed by a plug, B, of rubber, to serve as an eraser, or by a cap, a screw-plug, or other suitable means. The lower end of the case A has longitudinal slits 40 C formed in it, and has its edge bent inward slightly, as shown in Figs. 1 and 2, to enter an annular groove, D, in the middle part of the die E, to hold the said die in place, the slits C giving sufficient elasticity to the lower 45 part of the case A to allow the die E to be readily inserted and removed. The upper part of the die E is made of such a size as to fit into the case A, and its upper end is rounded, so that it can be readily inserted in the 50 case A. The lower part of the die E is ta-

pered, and has a screw-thread, F, cut in its inner surface, as shown in Fig. 5. The inner end of the perforation through the die E is flared, so that the lead G can be readily inserted in it. The lead G is made square or of 55 other desired angular form, and fits into the correspondingly-shaped interior of the pencil-tube H. The pencil-tube H has a circular flange, I, at each end, so formed as to fit into the interior of the case A so snugly that the 60 said tube will not be turned by the pressure of the lead G when being operated upon by the die E. The pencil-tube H may be somewhat shorter than the case A, and should be arranged with its forward end close to the inner end of the die E, so that the lead G will 65 be firmly supported against breakage while being used. In supplying the pencil-holder with a lead the die E is detached, a suitable lead, G, is inserted in the die E from its inner end, and the said die is turned until the forward end of the said lead projects for a 70 suitable distance, the screw-thread F cutting a screw-thread upon the angles of the said lead, and drawing it forward, as indicated in 75 Figs. 1 and 2. The rear end of the lead G is then inserted in the pencil-tube H, and the inner end of the die E is pushed into the end of the case. With this construction, by turning the die E in one direction, the lead G will 80 be forced outward into the position for use, and by turning the said die in the other direction the lead will be drawn inward, so that the pencil can be carried without danger of 85 breaking the point off the lead.

Having thus described my invention, what I claim as new, and desire to secure by Letters Patent, is—

1. A pencil-holder constructed substantially as herein shown and described, and consisting of the case A, having its lower end slitted and its end edge bent inward, the die E, having exterior groove, D, and interior screw-thread, F, and the pencil-tube H, having angular interior, as set forth. 90

2. In a pencil-holder, the case A, made substantially as herein shown and described, with its lower end slitted, and the slitted ends turned inward, to adapt it to receive a die and hold it by friction, as set forth. 95

3. In a pencil-holder, the die E, made substantially as herein shown and described, with exterior groove, D, and interior screw-thread, F, to adapt it to be held in place by friction and to cut a screw-thread upon an angular lead, in combination with a suitable case or holder, as set forth.
- 5 4. In a pencil-holder, the combination, with the die E, having interior screw-thread, of the

pencil-tube H, having angular interior, substantially as herein shown and described, and a case or holder, whereby the lead will be held from turning while being moved in and out by the said die, as set forth.

BERNHARD EYBEL.
